GASOLINE MOTOR FUEL

Helen I. Thayer, Pittsburgh, Pa., assignor to Gulf Research & Development Company, Pittsburgh, Pa., a corporation of Delaware

No Drawing. Filed June 11, 1959, Ser. No. 819,568

9 Claims. (Cl. 44—69)

This invention relates to gasoline compositions and particularly to gasoline motor fuels containing additives to impart ignition-control properties and oxidation stability to the fuels.

The trend in automotive design for several years has been toward increasing the compression ratio of the engine. The advantages in economy and efficiency that result from increased compression ratios have been known in the automotive industry for some time as evidenced by the fact that automobile manufacturers have been marketing automobiles with engine compression ratios of 9:1 or higher. In order to obtain smooth engine performance at high compression ratios, it has been necessary to employ fuels having a high octane number. Most fuels require the addition of organometallic anti-knock agents such as tetraethyl lead to obtain high octane numbers. The use of these additives has certain disadvantages in that the fuels containing them tend to leave deposits on the piston head, valves and walls of the combustion chamber of the engine and on the electrodes and insulators of the spark plugs. These deposits reduce the efficiency of the engine and may offset increased efficiencies obtained by high compression ratios. These deposits tend to build up in the engine and to increase the octane number requirement of the engine until an equilibrium octane number is reached. Thus, in engines that have been in operation for several hundred hours, the octane number required may be as much as 15 numbers higher than the requirement of that engine at the start of operation. For example, a clean engine which requires a gasoline having an octane rating of 75 in order not to knock may require octane values as high as 90 after the fuel deposits have accumulated on the engine parts.

These deposits comprising decomposition products of tetraethyl lead are material factors in raising the equilibrium octane requirement of an engine, but they are not the only cause of deposition in the engine. Thus, an increase in the octane number requirement is noted when gasolines to which no lead has been added are used as fuels. The increase in octane number requirement in these fuels is the result of deposits from incomplete combustion or decomposition of the gasoline and of gasoline additives other than tetraethyl lead. However, the octane number requirement increase is usually less with unleaded fuel than with leaded fuel.

Various scavenging agents have been added to fuels to overcome the detrimental effects of the deposition of lead compounds. These additives change the form of the lead compounds so they are more volatile and thus less likely to be deposited in the engine. For example, various volatile alkyl halides such as ethylene dibromide or ethylene dichloride have been used with tetraethyl lead to produce the corresponding halides of lead which are more volatile than the oxides. These additives have not been completely successful in overcoming the deposition of decomposition products. The decomposition products comprise various salts including the oxides, sulfates, bromides and chlorides of lead which have been found to alter the engine characteristics adversely when deposited in the combustion chamber of the engine.

As a matter entirely apart from the problem of preignition due to engine deposits, it has been found that cracked gasolines, polymer gasolines and blends containing these gasolines are unstable and tend to undergo

2

deterioration over a period of time. This difficulty is probably due to the presence of certain undesirable constituents which are subject to oxidative change and result in the formation of gums and color-imparting bodies in the gasoline. In contrast to the sludges formed in fuel oil, the gums formed in gasolines are soluble therein and do not appear as such except upon the evaporation of the gasoline. It is probable that at least a part of the gum and color formation is due to the polymerization of olefinic, diolefinic and other unsaturated hydrocarbons.

I have found that improved gasoline fuel compositions are obtained by the addition of small amounts of a reaction product of (a) primary, secondary or tertiary alkyl (cyclic or open-chain), alkenyl or alkylol mono- or diamines whose substituents contain 2 to 22 carbon atoms, preferably alkyl and alkenyl mono- and diamines, such as tertiarybutylamine or 3—"tallow"-aminopropylamine, and (b) complex anhydrides prepared by reacting a partially esterified orthophosphoric acid that contains 1 to 2 organic substituents, at least one of which is a hydrocarbon radical containing 5 to 22 carbon atoms and the other of which when present is a hydrocarbon radical containing 1 to 22 carbon atoms, such as the mono- and di(2-ethylhexyl) orthophosphates and a borylating agent such as boric acid, boric oxide or an anhydride of boric oxide and an aliphatic monocarboxylic acid, preferably a C_{1-8} unsubstituted acid such as acetic acid, in the ratio of about 0.5 to 6 moles of partially esterified orthophosphoric acid per mole of borylating agent, under conditions conducive to anhydride formation. The amines and the complex anhydrides are reacted in the ratio of 0.5 to 2 equivalents of anhydride per equivalent of amine. Good results are obtained by the use of about 0.002 to 1 percent of the reaction products, but other quantities can be used. The preferred gasoline soluble amine compounds for preignition suppressors are those which contain a large proportion of phosphorus in the molecule, for example, the reaction products formed from the borylated partially esterified orthophosphates and lower molecular weight amines such as tertiarybutylamine, propylamine, isopropylamine, etc. The percentage of phosphorus in the molecule is relatively less important in the compounds used as additives to suppress oxidation of the gasoline. Thus, the reaction products formed from the borylated partially esterified orthophosphates and the gasoline soluble higher fatty alkyl diamines, such as 3—"tallow"-aminopropylamine have been found to give excellent results as oxidation inhibitors.

When the addition products of this invention are used in gasoline in amounts corresponding to at least 0.1 times that theoretically required to convert the tetraethyl lead present in the gasoline to lead orthophosphate, they tend to reduce the over-all quantity of lead deposits and they also function to reduce the capacity of any lead deposits to preignite a gasoline air mixture. When used in any proportion described herein, they impart oxidation stability to the gasoline. It might appear that these compounds inhibit the oxidative changes and the polymerization of the olefins, diolefins and other unsaturated hydrocarbons present in the gasoline.

Preferred reaction products included by the invention are: the tertiarybutyl amine derivative of the anhydride formed from boric oxide and mono-di(2-ethylhexyl) orthophosphate (1:3 molar ratio) wherein the acid-amine equivalent ratio is 1:1; the 3—"tallow"-aminopropylamine derivative of the anhydride formed from boric oxide and mono-di(2-ethylhexyl) orthophosphate (1:3 molar ratio) wherein the acid-amine equivalent ratio is 1:2; the 3—"tallow"-aminopropylamine derivative of the anhydride formed from boric oxide and ethyl lauryl orthophosphate (1:1 molar ratio) wherein the acid-amine equivalent ratio

is 1:2; the 3-“tallow”-aminopropylamine derivative of the anhydride formed from boric oxide and monoctyl orthophosphate (1:2 molar ratio) wherein the acid-amine equivalent ratio is 1:2.

Specific examples of other reaction products whose use is included by this invention are amine derivatives of 0.5, 1 or 2 equivalents of the anhydrides formed from boric oxide and ethyl lauryl monoacid orthophosphate (1:1 molar ratio); boric acid and di(2-ethylhexyl) monoacid orthophosphate (1:0.8 molar ratio); the anhydride of boric oxide and acetic acid and dioctyl monoacid orthophosphate (1:3 molar ratio); boric oxide and diamyl monoacid orthophosphate (1:3 molar ratio), boric oxide and monoctyl diacid orthophosphate (1:2 molar ratio); and one equivalent of any of the following: 2-ethylhexylamine, 3-isopropylamine, tertiarybutylamine, n-octylamine, n-decylamine, n-dodecylamine, n-tetradecylamine, n-octadecylamine, N,N - dibuylisopropylamine, 3 - isopropylaminopropylamine, N-octadecenyl ethylene diamine, 3-dodecylaminopropylamine, and those mono- and diamines where the respective nitrogen substituents are mixed alkyl and alkenyl groups obtained from naturally occurring fats and oils, e.g., tallow, soybean oil, coconut oil and the like. In such instances, the aliphatic N-substituent will be monovalent straight-chain hydrocarbon radicals containing an even number of carbon atoms from 8 to 22. Examples of such mixtures are: 3-“tallow”-aminopropylamine, 3 - “soya” - aminopropylamine, 3-“coco”-aminopropylamine, cocoamine, etc.

From the foregoing discussion, it will be seen that the reaction products whose use is included by this invention can be illustrated by the structural formula

where R is an alkyl, alkenyl or alkylol group containing 2 to 22 carbon atoms, x is 0 or 1, R' and R'' are hydrogen when x is greater than 0 or hydrogen, alkyl, alkenyl or alkylol groups of the same kind as R when x is 0, y is an integer from 0 to 3 but is zero only when x is zero, H is hydrogen, N is nitrogen, z is a number from 5 to 10, A is an acid radical derived from a borylated partially esterified orthophosphate of the kind described hereinabove, and w is 1 to 4, and z and w are not necessarily whole numbers.

The preparation of these compounds is not a part of this invention and they can be prepared in any suitable manner. The preferred method of preparing these compounds is disclosed in the copending application of Helen I. Thayer, Serial No. 819,566, filed of even date herewith. As described in that application, they can be prepared by adding the desired amine to a selected complex acidic anhydride of the kind defined above, in the proportion described herein; preferably while maintaining the reaction temperature at 40° to 60° C. Heat is generally evolved in this addition so it is normally desirable to add the amine gradually to control temperatures. Although the reactions will take place spontaneously without addition of heat, it is sometimes desirable to heat the reactants moderately before introducing them into the reaction in order to facilitate intermixture. After the addition is complete, the slurry is cooled and a semi-solid melt or a viscous oily product is recovered.

The process used in preparing the complex anhydride is also described briefly in my copending application Serial No. 819,566, and in greater detail in my copending application Serial No. 819,569, directed thereto. As indicated in the latter, the process can differ somewhat depending on the borylating agent used. A general procedure in synthesizing these compounds when boric oxide or orthoboric acid is the borylating agent comprises refluxing a solution of the orthophosphoric acid ester in a solvent such as benzene in the presence of about 0.5 to about 6

moles of the phosphoric acid ester per mole of the borylating agent. Refluxing is continued until no more water is formed, usually from about 0.5 to about 24 hours. Any unreacted borylating agent is removed by filtration and the product is recovered by distillation to remove the solvent. The procedure is essentially the same when an anhydride of boric oxide and an aliphatic monocarboxylic acid is used as the borylating agent in that the reaction progresses satisfactorily in the absence of the solvent. The temperature at which these reactions are carried out varies with the borylating agent and the nature of the by-product evolved in the reaction. The temperature must be high enough to drive off the water or aliphatic monocarboxylic acid evolved, but below the decomposition temperature of the product. Thus, the temperature may be as low as 50° C. or as high as 145° C. Both the reaction involving formation of the anhydride and the subsequent reaction of this product are carried out at atmospheric pressure.

The addition agents of this invention are useful in a wide range of proportions. The amount used is dependent on the function to be performed by the additive, for example, the amount of additive to be added to the gasoline in order to reduce the octane requirement increase, minimize preignition, effectively decrease wild ping count and decrease the average noise requirement, depends on the deposit forming characteristics of the fuel when burned in an internal combustion engine. When the fuel is a leaded gasoline, the amount of compound to be added can be determined by the amount of tetraethyl lead which is present. The most satisfactory approach, in view of the fact that the molecular weights of the compounds vary from compound to compound, is to add that amount of compound necessary to convert the lead present to lead orthophosphate. While improved results can be obtained with very small amounts, amounts corresponding to at least about 0.1 times that theoretically required to convert the lead to lead orthophosphate are preferred. Especially good results are obtained by using about 0.2 to about 0.5 times the theoretical amount required. In general, I prefer to use an amount not more than the amount theoretically required to convert all the lead to lead orthophosphate. Amounts greater than the theoretical amount can be employed, but for economic reasons, I prefer to use only the amount required to give the desired improvement. Therefore, I prefer to employ an amount equal to about 0.2 to about 0.5 times that theoretically required to convert the lead to lead orthophosphate. In view of the fact that the amount of tetraethyl lead varies from gasoline to gasoline, it is difficult to state on a weight basis the amount of a particular compound required. Most gasolines marketed today contain between about 1 and about 3 cubic centimeters of tetraethyl lead per gallon of gasoline. Based upon a gasoline having a gravity of about 54° API and containing about 1 cubic centimeter of tetraethyl lead, I have determined that the amount of the tertiarybutylamine derivative of borylated mono-di(2-ethylhexyl) orthophosphate, for example, corresponding to about 0.1 to about 1.0 theories is about 0.004 to about 0.044 percent by weight of the gasoline.

If the same gasoline contains 3 cubic centimeters of tetraethyl lead, then the amount of tertiarybutylamine derivative of the borylated mono-di(2-ethylhexyl) orthophosphate is about 0.013 to about 0.13 percent by weight of the gasoline. Thus, the normally useful concentration for a 54° API gasoline containing about 1 to about 3 cubic centimeters of tetraethyl lead per gallon is about 0.004 to about 0.13 percent by weight of the gasoline. Although greater concentrations can be employed to advantage in some instances, no additional benefits with respect to preignition are achieved by the use of greater concentrations. For most currently marketed commercial gasolines, about 0.001 to about 0.15 weight percent of the tertiarybutylamine derivative of the borylated mono-

di(2-ethylhexyl) orthophosphate is usually sufficient to achieve a satisfactory reduction of the preignition tendencies of the fuel. The amount within this range should, of course, be sufficient to incorporate between 0.1 and about 1.0 times that theoretically required to convert the lead to lead orthophosphate.

It will be understood, of course, that the optimum amount on a weight basis for tertiarybutylamine reaction product may not be the optimum amount for another amine derivative of another borylated orthophosphate or another amine derivative of the borylated mono-di(2-ethylhexyl) orthophosphate compound. One reason for this is that the effectiveness of the compounds may vary from one compound to another. Another reason is the obvious differences in the molecular weights of the compounds in this series so that to obtain an equivalent amount of phosphorus when using a compound having higher molecular weight it is necessary to use a different amount of the compound on a weight basis.

The amount of the reaction products required to impart oxidation stability to the gasoline can be calculated on a different basis since the gum formation or discoloration is probably caused by the presence of polymers or compounds containing oxygen or sulfur rather than to the presence of tetraethyl lead in the gasoline. Obviously the various salts of the herein disclosed class do not possess exactly identical effectiveness, and the most advantageous concentration for each salt will depend to some extent upon the particular compound used. Also, the minimum effective inhibitor concentration may vary somewhat according to the specific nature of the gasoline to be inhibited. In general, however, the herein disclosed salts are useful in concentrations of as little as about 0.001 percent to about 1.0 percent by weight of the composition. Major improvement in the storage stability characteristics of gasolines is usually obtainable by incorporation therein of about 0.005 to 0.5 weight percent of the herein disclosed class of salts.

The amine derivatives of the borylated partially esterified orthophosphates of this invention can be incorporated in the base gasoline fuel composition in any suitable manner. Thus, they can be added as such to the gasoline in the form of dispersions or solutions in solvents such as butanol, diethylene glycol, monobutyl ether, benzene, toluene, heptane, kerosene, gasoline, mineral oil or the like, which solvents do not themselves contribute to the preignition- or oxidation-inhibitive characteristics of the ultimate composition. If desired the amine derivatives of the borylated partially esterified orthophosphate anti-preignition or anti-oxidant agents can be incorporated in the gasoline fuel compositions in admixture with other materials designed to improve one or more properties of the gasoline such as anti-stalling agents, corrosion inhibitors, anti-knock agents, e.g., tetraethyl lead, deicing agents, dyes, and the like.

Gasoline compositions of this invention can be further illustrated by the following specific examples:

EXAMPLE 1

A motor gasoline composition according to this invention was prepared by incorporating in a sample of conventional commercial gasoline, 0.479 gram per gallon (0.017 weight percent) of the tertiarybutylamine derivative of the anhydride prepared by reacting 1.0 mole of boric oxide with 3.1 moles of mono-di(2-ethylhexyl) orthophosphate, a mixture of mono- and diesters, by adding the amine to the borylated mono-di(2-ethylhexyl) orthophosphate while maintaining the reaction temperature at about 40° C., wherein the anhydride-amine equivalent ratio was 1:1. The base gasoline was a blended gasoline made up of 22.1 parts catalytically cracked gasoline, 43.4 parts alkylate, 30.5 parts "Platformate," and 4.0 parts spent butane and contained about 1.9 cubic centimeters (about 3.13 grams) of tetraethyl lead per gallon of gasoline. The tertiarybutylamine derivative of

borylated mono-di(2-ethylhexyl) orthophosphate thus comprised 0.2 times the theoretical amount required to convert the tetraethyl lead to lead orthophosphate. Typical samples of the base gasoline and the base gasoline containing 0.479 gram per gallon of the tertiarybutylamine derivative of borylated mono-di(2-ethylhexyl) orthophosphate had the following inspections:

EXAMPLE 2

A gasoline composition demonstrating the excellent wild ping count improvement characteristics of these additives was prepared by incorporating 0.983 gram (0.035 weight percent) of the compound of Example 1, in a gallon of gasoline. The base gasoline was a blend of 41.9 parts catalytically cracked gasoline, 19.1 parts polymer, 34.9 parts straight-run gasoline and 4.1 parts butane. The base gasoline contained about 1.6 cubic centimeters (2.62 grams) of tetraethyl lead per gallon of gasoline. The tertiarybutylamine derivative of borylated mono-di(2-ethylhexyl) orthophosphate thus comprised about 0.43 times the theoretical amount required to convert the tetraethyl lead to lead orthophosphate. Typical samples of the base gasoline and base gasoline containing 0.035 weight percent of the tertiarybutylamine derivative of borylated mono-di(2-ethylhexyl) orthophosphate had the following inspections:

EXAMPLE 3

A suitable composition was prepared in the manner of the foregoing Example 2, by incorporating 2.45 grams per gallon (approximately 0.088 weight percent) of the reaction product of Example 1 in a sample of conventional commercial gasoline. The tertiarybutylamine derivative of borylated mono-di(2-ethylhexyl) orthophosphate was equivalent to about 1.08 times the theoretical amount required to convert the lead of the tetraethyl lead to lead orthophosphate.

EXAMPLE 4

An additional gasoline composition having excellent oxidation stability characteristics was prepared by incorporating in the gasoline 4.2 grams per gallon (approximately 0.154 weight percent) of the 3-“tallow”-aminopropylamine derivative of the anhydride prepared by reacting 1 mole of boric oxide with 1 mole of ethyl lauryl orthophosphate, by adding the amine to the borylated orthophosphate while maintaining the reaction temperature at about 40° to 60° C. The acid-amine equivalent ratio in the derivative was 1:2. The base gasoline was an unleaded pressure distillate. Typical samples of base gasoline had the following inspections:

EXAMPLE 5

Another suitable composition was prepared in accordance with the foregoing Example 4 by incorporating in the base gasoline of Example 4, 4.3 grams per gallon (approximately 0.155 weight percent) of the reaction product prepared by reacting 2 equivalents of 3-“tallow”-aminopropylamine with 1 equivalent of the anhydride formed in the reaction of 1 mole of boric oxide with 2 moles of mono-octyl diacid orthophosphate, by adding the amine to the borylated orthophosphate while maintaining the reaction temperature at about 40° to 60° C.

EXAMPLE 6

An additional suitable composition was prepared in accordance with the foregoing Example 4 by incorporating in the base gasoline of Example 4, 2.0 grams per gallon (0.072 weight percent) of the derivative prepared by reacting 1 equivalent of 3-“tallow”-aminopropylamine with 2 equivalents of the anhydride prepared from the reaction of 1 mole of boric oxide with 3 moles of the mono-di(2-ethylhexyl) orthophosphate of Example 1, by adding the amine to the borylated orthophosphate while maintaining the reaction temperature at about 40° to 60° C.

EXAMPLE 7

Another preferred composition was prepared by incorporating the same compounds and the same gasoline in the same proportions as in Example 6 with the exception that the compound was prepared to have an acid to amine equivalent ratio of 1:2.

An appreciable reduction in preignition due to deposits formed by combustion of gasoline containing tetraethyl lead is achieved by the use of the foregoing gasoline fuel composition of Examples 1, 2, 3, in internal combustion engines of the gasoline-powered, spark ignition type, for

example, when the compositions described in these examples are burned in an internal combustion engine operated under conditions wherein noise including preignition, knock and rumble would normally be encountered, such engine noise is considerably less than the noise encountered when the base gasoline is used.

In order to illustrate the improved preignition characteristics obtained with a fuel of this invention, a test was employed in which the fuel was burned in a multi-cylinder Cadillac engine. This engine has a compression ratio of 10:1.

In this test the engine was operated on a cycling schedule consisting of 3 minutes at 1500 r.p.m. at 15 brake horsepower load followed by 1 minute idle at 460 r.p.m. The spark advance in each instance was the manufacturer's setting. The coolant temperatures in and out were 150 ± 5 ° F. and 160 ± 5 ° F., respectively. The oil temperature in all instances was 180 ± 5 ° F. At the end of each 24 hour period during the above-described cycling schedule noise requirement determinations were made. After the noise requirement determinations were made, the engine was put back on the cycling schedule for another 24 hours. The cycling and noise requirement tests were continued for nine 24-hour periods. The noise requirement determinations were made according to 3 successive steps. If noise was encountered in step 1, then steps 2 and 3 were omitted. If noise was encountered in step 2, then only step 3 was omitted. Noise in this test is intended to include preignition, normal knocking and rumble. The 3 successive steps of the test are as follows:

(1) At a speed of 1100 r.p.m. the throttle is opened to detent (that is, the rear barrels of the carburetor are just open) at 1 inch mercury intake manifold vacuum.

(2) The engine speed is increased to 1300 r.p.m. at 3 inch vacuum.

(3) The engine is accelerated at 10 inch vacuum from 1300 to 2000 r.p.m., standard spark, and held at this setting for 3 seconds (throttle wide open at end of 3 seconds period).

Aural observations are made at steps 1, 2 and 3 and preignition, rumble and knock are recorded.

Ratings are made on the tank fuel (99 research octane number) and the actual noise requirement determined by the use of a set of commercial reference fuels having octane numbers up to an octane number of 113.5. For noise requirements in the range of 113.5 to 120, leaded iso-octane was used. Octane numbers above 100 are expressed in the approved extension scale, Wiese octane numbers, which are:

Performance No.—100 + 100
3

The data set forth in Table I summarizes the results obtained when the test engine was operated under the above test procedure with the base gasoline and the base gasoline containing 0.2 times the theoretical amount of the tertiarybutylamine derivative of mono-di(2-ethylhexyl) orthophosphate of Example 1 required to convert the lead to lead phosphate.

TABLE I.—MAXIMUM NOISE REQUIREMENTS (WIESE) OCTANE NO.

75 1 Sustained violent preignition.

TABLE III.—AVERAGE CHANGE IN COMPRESSION RATIO

Example 1 Composition	Base Gasoline
0.03.....	0.38

The data in Table I indicate that a reduction in engine octane requirements for a noise-free operation is obtained by the use of the gasoline compositions of this invention. Thus, the octane requirement was reduced from 117 in the base gasoline to 100 in the gasoline containing the additive. The data in Table II clearly indicate that the addition agents of this invention effect a remarkable increase in the average time in which the engine can be operated before violent preignition occurs. Thus, where the engine was able to operate for only 36 hours without sustained violent preignition (SVPI) when using the base fuel, the same engine was able to operate for more than 192 hours without violent preignition using the gasoline composition of Example 1. The data in Table III show a much smaller increase in the compression ratio when the fuel composition of Example 1 is compared with the base gasoline.

The gasoline composition of Example 1 was tested in a single cylinder engine and compared with an uninhibited base fuel to show the effect of the additives on the octane requirement increase. This test was conducted in a single cylinder L-head engine with a 7:1 compression ratio. The engine was operated on a cycling schedule alternating between the following conditions:

Time, Sec.....	50	150
Speed, r.p.m.....	600	900
Load.....	None	Full
Air-Fuel Ratio.....	11:1	13:1
Ignition Timing.....	TDC	TDC
Coolant Temp., °F.....	150±3	150±3
Oil Temp., °F.....	140±5	140±5
Carburetor, Intake Air Temp., °F.....	105±2	105±2
Humidity Control.....	Ice Tower	Ice Tower
Test Duration, 160-170 hours.		

The octane requirement evaluation was made under conditions of the full throttle part of the cycle. Reference fuel blends of isoctane and normal heptane were used. Knock determinations were made aurally as the ignition time was varied to the point of trace knock. Three or more reference fuel blends which knock between 5° ATC and 15° BTC were rated and the requirements at TDC were interpolated from the plot of these data.

Throughout the test a wild ping counter in the form of a second dummy plug detected any uncontrolled combustion which occurred during 153° BTC and 7° ATC of the cycles. The number of cycles during the test in which such spontaneous ignition of the fuel charge occurred were counted. The wild ping counts gave a quantitative indication of the effectiveness of the fuel in controlling preignition. The results of this test are tabulated below:

TABLE IV.—OCTANE REQUIREMENT INCREASE TEST

	Example 1 Composition	Base Gasoline
Octane Requirement, Hrs.....	77.5@160 590	78.0@162 5000
Wild Ping Count Accumulation.....		

The data in Table IV indicate no adverse effect upon octane requirement and an exceptional decrease in the wild ping count over a period of 160 hours. Thus the wild ping count was reduced from 5000 (control) to 590 total accumulative counts over a period of 160 hours.

The utility of the herein disclosed reaction products as gasoline antioxidants has been demonstrated by subjecting unstable gasoline samples containing the various agents disclosed herein to the standard oxidation stability

test ASTM D525-49. In this test the gasoline sample is introduced into an oxidation bomb and oxygen is added to a pressure about 100 pounds p.s.i. The charged bomb is placed in a boiling water bath and the gas pressure in the bomb is recorded. The end of the induction period, i.e., the point at which rapid absorption of the oxygen by the gasoline takes place, is the time when a sharp drop in pressure (at least 2 p.s.i. in 15 minutes) occurs, is noted. The results obtained by the foregoing test are presented in Table V below:

TABLE V.—ADDITIVE CONCENTRATION

	G./100 grams Gas- oline	Induction Period in Minutes
1. Base gasoline.....	0.154	121
2. Gasoline composition of Example 4.....	0.155	355
3. Gasoline composition of Example 5.....	0.0721	388
4. Gasoline composition of Example 6.....	0.0721	218
5. Gasoline composition of Example 7.....	0.0721	279

Compositions 2, 3, 4 and 5 in Table V are specific embodiments of this invention. Comparison of the induction periods of these compositions with those for the base gasoline composition 1 indicates the remarkable improvement obtainable by the salts of this invention. Comparison of compositions 4 and 5 show the improved properties when the acid-amine equivalent ratio is changed from 2:1 to 1:2.

It will be understood that the foregoing embodiments of this invention are merely illustrative and that other members of the class of addition agents of this invention can be substituted therein in the same or equivalent concentrations within the herein disclosed range to prepare gasoline compositions having greatly improved characteristics.

Specific examples of other reaction products that are suitable for the purposes of this invention are the amine derivatives of 0.5, 1 or 2 equivalents of the anhydrides formed from boric oxide and ethyl lauryl monoacid orthophosphate (1:1 molar ratio); boric acid and di(2-ethylhexyl) monoacid orthophosphate (1.3:1 molar ratio); the anhydride of boric oxide and acetic acid and diethyl monoacid orthophosphate (0.3:1 molar ratio); boric oxide and diethyl monoacid orthophosphate (0.3:1 molar ratio); boric oxide and monoethyl diacid orthophosphate (0.5:1 molar ratio); and one equivalent of any of the following: 2-ethylhexylamine, 3-isopropylamine, tertiarybutylamine, n-octylamine, n-decylamine, n-dodecylamine, n-tetradecylamine, n-octadecylamine, N,N-dibutylisopropylamine, 3-isopropylaminopropylamine, N-octadecenyl ethylene diamine, 3-dodecylaminopropylamine, 3-tallow-aminopropylamine, 3-soya-aminopropylamine, 3-coco-aminopropylamine, cocoamine, etc.

If desired, the gasoline compositions of this invention may contain, in addition to the additives disclosed herein, other improvement agents as indicated above, for example, anti-knock agents such as tetraethyl lead, corrosion inhibitors such as ammonium salts of dialkyl phosphates, dyes, gum inhibitors and/or antioxidants such as

N,N'-di-secondary-butyl-para-phenylenediamine
2,4-dimethyl-6-tertiary-butylphenol
2,6-di-tertiarybutyl-4-methylphenol,

and other conventional additives.

While my invention is described above with reference to various specific examples and embodiments, it will be understood that the invention is not limited to such examples and embodiments and may be variously practiced within the scope of the claims hereinafter made.

I claim:

1. A gasoline motor fuel comprising a major amount of a hydrocarbon mixture boiling in the gasoline range and containing about 0.001 to about 1 percent by weight of the composition of a reaction product of (a) an amine

selected from the group consisting of primary, secondary and tertiary alkyl, alkenyl and alkylol mono- and diamines whose substituents each contain 2 to 22 carbon atoms, and (b) an anhydride prepared by reacting a partially esterified orthophosphoric acid that contains 1 to 2 organic substituents per molecule, at least one of whose substituents is a hydrocarbon radical containing 5 to 22 carbon atoms, and the other substituent of which when present is a hydrocarbon radical containing 1 to 22 carbon atoms, with a borylating agent selected from the group consisting of boric acid, boric oxide, and an anhydride of boric oxide and an aliphatic monocarboxylic acid, in the ratio of about 0.5 to 6 moles of said partially esterified orthophosphoric acid to one mole of borylating agent under conditions conducive to anhydride formation, said amine and said anhydride being reacted in the proportion range of about 0.5 to 2 equivalents of anhydride per equivalent of amine.

2. A gasoline motor fuel comprising a major amount of a hydrocarbon mixture boiling in the gasoline range and containing tetraethyl lead in an amount normally tending to cause preignition of said fuel in the combustion chamber of a spark ignition, reciprocating internal combustion engine, and a minor amount, sufficient to inhibit such preignition, of a reaction product of (a) an amine selected from the group consisting of primary, secondary and tertiary alkyl, alkenyl and alkylol mono- and diamines whose substituents each contain 2 to 22 carbon atoms, and (b) an anhydride prepared by reacting a partially esterified orthophosphoric acid that contains 1 to 2 organic substituents per molecule, at least one of whose substituents is a hydrocarbon radical containing 5 to 22 carbon atoms, and the other substituent of which when present is a hydrocarbon radical containing 1 to 22 carbon atoms, with a borylating agent selected from the group consisting of boric acid, boric oxide, and an anhydride of boric oxide and an aliphatic monocarboxylic acid, in the ratio of about 0.5 to about 6 moles of said partially esterified orthophosphoric acid per mole of borylating agent, under conditions conducive to anhydride formation, said amine and said anhydride being reacted in the proportion range of about 0.5 to about 2 equivalents of anhydride per equivalent of amine.

3. The gasoline composition of claim 2 where said minor amount is about 0.1 to 1 times the theoretical amount required to convert the lead in the tetraethyl lead to lead orthophosphate.

4. The gasoline composition of claim 2 where said minor amount is about 0.2 to 0.5 times the theoretical amount required to convert the lead in the tetraethyl lead to lead orthophosphate.

5. The gasoline composition of claim 1 where the amine is tertiarybutylamine, the partially esterified orthophosphate acid is mono-di(2-ethylhexyl) orthophosphate, the borylating agent is boric oxide, the molar ratio of borylating agent to phosphate is about 1:3, and the amine to anhydride equivalent ratio is about 1:1.

10 6. The gasoline composition of claim 1 where the amine is 3-“tallow”-aminopropylamine, the partially esterified orthophosphate acid is ethyl lauryl orthophosphate, the borylating agent is boric oxide, the molar ratio of borylating agent to phosphate is about 1:1, and the amine to anhydride equivalent ratio is about 2:1.

15 7. The gasoline composition of claim 1 where the amine is 3-“tallow”-aminopropylamine, the partially esterified orthophosphate acid is mono-octyl diacid orthophosphate, the borylating agent is boric oxide, the molar ratio of borylating agent to phosphate is about 1:2, and the amine to anhydride equivalent ratio is about 2:1.

20 8. The gasoline composition of claim 1 where the amine is 3-“tallow”-aminopropylamine, the partially esterified orthophosphate acid is mono-di(2-ethylhexyl) orthophosphate, the borylating agent is boric oxide, the molar ratio of borylating agent to phosphate is about 1:3, and the amine to anhydride equivalent ratio is about 2:1.

25 9. The gasoline composition of claim 1 where the amine is 3-“tallow”-aminopropylamine, the partially esterified orthophosphate acid is mono-di(2-ethylhexyl) orthophosphate, the borylating agent is boric oxide, the molar ratio of borylating agent to phosphate is about 1:3, and the amine to anhydride equivalent ratio is about 1:2.
